UNITED STATES PATENT OFFICE

169,974

MUSIC BOX NURSERY LAMP

Robert Goldman and Roy R. Nemzer, South Hempstead, N. Y., assignors to Bo-Low Lamp Corp., Brooklyn, N. Y., a corporation of New York

Application February 16, 1953, Serial No. 23,642

Term of patent 14 years

(Cl. D48—20)

To all whom it may concern:

Be it known that we, Robert Goldman and Roy R. Nemzer, both citizens of the United States and residents of South Hempstead, in the county of Nassau, State of New York, have invented a new, original, and ornamental Design for a Music Box Nursery Lamp, of which the following is a specification, reference being had to the accompanying drawing, forming a part thereof, and of which

Fig. 1 is a front perspective view of a music box nursery lamp, showing our new design,

Fig. 2 is a rear perspective view thereof, and
Fig. 3 is a front perspective view of the music

box nursery lamp shown in Figs. 1 and 2 with the cradle in an opposite extreme position.

We claim:

The ornamental design for a music box nursery lamp, as shown.

ROBERT GOLDMAN.
ROY R. NEMZER.
